(57) **CLAIM**

The ornamental design for a handleset grip, as shown and described.

DESCRIPTION

FIG. 1 is a perspective view of our new design for a handleset grip;

FIG. 2 is a front elevational view thereof;

FIG. 3 is a top plan view, the bottom plan view being a mirror image thereof;

FIG. 4 is a right side elevational view, the left side being a mirror image thereof; and,

FIG. 5 is a back elevational view thereof.

The broken line showing of the background environment in FIGS. 1–4 and the diameter of the attachment hole in FIG. 5 are for illustrative purposes only and forms no part of the claimed design.
